United States Patent Office

Des. 212,238

Patented Sept. 17, 1963

212,238

LOUDSPEAKER SUPPORT STAND

Joseph Belotte, P.O. Box 541,
Arlington, Va. 22216

Filed Aug. 23, 1967, Ser. No. 8,353

Term of patent 14 years

(Cl. D33—3)

Fig. 1

Fig. 3

Fig. 2

Fig. 4

Fig. 5

FIGURE 1 is a front perspective view of a loudspeaker support stand showing my new design;

FIGURE 2 is a top plan view thereof;

FIGURE 3 is a side elevational view thereof; the opposite side being similar;

FIGURE 4 is a front elevational view thereof; and

FIGURE 5 is a rear elevational view thereof.

I claim:

The ornamental design for a loudspeaker support stand, substantially as shown.
